UNITED STATES PATENT OFFICE.

JOSEPH P. MEYER, OF ROCHESTER, NEW YORK.

FLUSHING VALVE.

Application filed August 9, 1922. Serial No. 580,744.

To all whom it may concern:

Be it known that I, JOSEPH P. MEYER, a citizen of the United States, and residing at Rochester, Monroe County, State of New York, have invented certain new and useful Improvements in Flushing Valves, of which the following is a specification.

This invention relates broadly to valve control mechanism and embodies means by which a valve is automatically closed at a definite predetermined interval of time after it is opened and which includes means by which the time which elapses between opening and closing may be easily regulated and controlled by the user as desired. It is particularly adapted for use with flushing valves and is shown as so applied, but it will be understood that it is not confined to that use but includes novel features of construction adapted for various uses. It includes a simple timing means which is both energized and set in operation through the movement of mechanism in opening the valve and it acts to release mechanism tending to close the valve and takes no other part in the closing action. The specific timing means shown resembles in many respects and operates on the same principle as the well known hour-glass, but it is made of special form and so mounted, moved and related to other elements of the device that it will be set for the timing operation by the valve opening means when it operates and will when its timing action is completed and the material has passed from one chamber to the other, automatically move on its support due to the change in the center of gravity and release the means for closing the valve and permit it to operate. It is semi-cylindrical in outline with a rotary supporting shaft having its axis coincident with the center line of the cylinder and the chambers are connected on a radial plane midway between the ends of the segment considered circumferentially by a narrow opening extending radially and means is provided for regulating the width of that opening so as to regulate the time of operation. There is a temporarily acting positive stop for preventing overthrow of the timer when it is turned to operating position by the opening of the valve through meshing gear segments and there is a yielding stop for thereafter preventing further turning movement until it has finished its timing action and the connection between it and the valve is of

such character as to permit limited further turning without turning the valve when the resistance of the yielding stop is overcome. The novel features will be more fully understood from the following description and claims taken with the accompanying drawings.

In the drawings:

Fig. 1 is a side view of a device embodying the invention;

Fig. 2 is a plan view of the device;

Fig. 3 is a vertical section on the line 3—3 of Figure 2 showing the parts in position when the valve is closed;

Fig. 4 is a view similar to that of Figure 3 showing the parts in the position occupied when the valve is open;

Fig. 5 is a vertical section on the line 5—5 of Figure 2;

Fig. 6 is a horizontal cross section of one of the chambers of the timing device taken on the line 6—6 of Figure 7 looking down;

Fig. 7 is a vertical section through the timing device taken on the line 7—7 of Figure 1; and

Fig. 8 is a detailed sectional view of portion of the valve casing and valve showing the interengaging stops for limiting relative rotary movement.

In the embodiment of the invention shown in the drawing there is a water supply pipe 10 making connection in the usual way with the valve casing 11 and the pipe 12 connected to the valve casing on the other side of the valve is what is called the flushing pipe leading downward to the place desired and as usual is of larger diameter than the supply pipe 10. The valve casing 11 has an opening 13 through it circular in section and slightly tapering in which the rotary valve 14 fits. At the inner end of the valve 14 there is a disk 15 having its outer periphery at its inner portion fitting within the opening 13 in the valve casing and spaced from the inner end of the valve 14 and it has a peripheral flange at its outer portion fitting the valve casing around the opening. This disk has openings 16 through it and pins 17 projecting from the inner end of the valve fit in these openings and serve to hold the disk 15 in position and prevent relative rotation. The disk 15 also has a central opening through which a screw 18 freely passes and this screw engages threads

in an opening in the end of the valve 14 and has a head 19 at its outer end some distance from the face of the disk 15. A coiled spring 20 surrounds this screw between disk 15 and its head 19, thus in cooperation with the disk 15 bearing against the surface of the valve casing tending to yieldingly move the valve 14 inward in the valve casing and preserving a tight fit of the valve in the casing. The valve 14 has extending transversely through it an elongated opening 21 shown in Figure 5 and in dotted lines in Figure 2, thus connecting the pipe 10 to pipe 12 when in proper position. A reduced cylindrical portion 22 on the valve 14 projects beyond the end of the valve casing and an operating arm 23 fits at one end in a socket 24 in this extension and extends radially for the purpose of moving the valve in a rotary direction for opening. A coiled spring 25 surrounds this reduced cylindrical portion between the arm 23 and the valve casing, one end being rigidly connected to the valve casing and the other end having a hook 26 engaging the operating arm 23, as seen in Figures 1 and 5. This spring is under tension when the valve is closed and by its engagement with the operating arm 23 always tends to close the valve. A rigid pin 27 projects from the end of the valve casing near the valve opening and a fixed stop 28 is mounted on the valve 14 projecting from the shoulder 29 outwardly and radially and is in the path of the pin 27 as the valve rotates and this pin and stop are so related that they will make contact as shown in Figure 3, when the valve is closed preventing further movement in the closing direction.

In turning the valve 14 to open position by the manually operable handle arm 23 its movement is limited by the contact of the fixed stop 28 carried by the valve with the fixed stop 30 secured to the end of the valve housing, as shown in Figure 4. There is an automatic catch 31 in the form of an elongated longitudinally curved rod pivoted at 32 to a fixed projection from the valve casing near its end 33 which is normally in the path of the stop 28 carried by the valve, the end 33 being yieldingly held inward in that path by a leaf spring 34 secured to the outer surface of the valve housing. The inner surface of the catch 31 from the pivot 32 to the end 33 is at an incline so that the stop 28 when the valve is moved to open position will move it outwardly against the tension of the spring and it will act as an automatic stop preventing return movement of the valve under the influence of spring 25 after it is fully opened. It will be noted, however, by reference to Figure 4 that the stop 28 moves a short distance beyond the end 33 of the catch before striking the stop 30

ending the opening movement and when the operating arm 23 is released, the spring will cause a slight reverse movement of the valve bringing the stop 28 into engagement with the catch 31.

The present invention embodies automatic means set in operation by the opening of the valve for releasing it from the catch 31 and allowing it to close at the expiration of a predetermined time after it is opened and this automatic means includes a timer 35, which operates on the principle of an hour-glass. As shown particularly in Figure 1, the timer is in the outward form of a segment of a cylinder and slightly more than half of the cylinder and is mounted on a rotary supporting shaft 36 which is concentric with the cylindrical surface of the segment and which is supported by a bearing in the bar 37 which is rigidly connected at 38 to a part of the valve casing and which extends longitudinally of the inlet pipe 10. The segmental timer is preferably made of thin metal 39 but one end has openings closed by glass 40 whereby it is possible to see what is taking place inside the chamber formed in the segment of the cylinder. The open space within the segment is divided into two chambers 41 and 42 by inclined wall surfaces 43, 44 of chamber 41 extending from the ends at a sharp angle to a point near the center line but leaving a narrow radial opening 45 between their inner edges. Similar inclined wall surfaces 46 and 47 extend from the end walls of chamber 42 inwardly at an angle to the margins of the opening 45 forming an elongated narrow opening in line with the edges of wall 43 and 44. A thin plate valve 48 having a straight inner edge is mounted in the segment in such position as to slide laterally of the opening 45 between the ends of the wall sections 44 and 46 with a close fit and may be moved inwardly so that its inner edge will enter the opening on one side thus regulating its width. This valve member may be operated by a screw threaded bolt 50 having screw threaded engagement with the ear 51 on the valve 48 and passing through the fixed part 53 of the side wall of the segment and having a fixed washer 54 fitting against the inner surface of the side wall thus preventing its longitudinal movement. It may have a kerf in its end for turning by a screw driver or may be of any other suitable shape for engagement by a tool for turning. Fluid material such as sand 55 is placed in the container formed in the cylindrical segment and may be sufficient in amount to practically fill one of the chambers which are on opposite sides of the opening 45 so that it may pass from one chamber to the other as in an hour-glass when the timer is inverted. The amount of sand and the size of the opening 45 of course

control the time which will elapse during the passage of the sand from one chamber to the other and the time therefore can be controlled by the movement of valve 51 to 5 the position which will permit the operation to be completed within any time within limits which may be desired. The time for different adjustments may be determined by experiment.

- 10 The shaft 36 of the timer segment 35 has secured to it a gear segment 56 having teeth which engage teeth on gear segment 57 which is mounted on a screw threaded pin 58 which enters a screw threaded socket 59 in the end of the cylindrical projecting portion 22 of the valve 14. The gear segment 57 has a short slot 60 concentric with the axis of the valve and a pin 61 passes through that slot and engages the end of 15 the valve member 22 whereby there may be a short relative rotary movement between the valve and the gear segment 57. Figures 1 and 3 show the arrangement of the parts when the valve is closed and it will be 20 noted that the timer segment 35 is in a position on that side of its axis which is nearest to the valve with the chamber 41 in a position substantially above chamber 42 so that the fluid material will be in the lower chamber 42, as illustrated in Figure 7. When the handle arm 23 is manually turned to the position shown in Figure 4 the timer segment is turned to the dotted line position shown in Figure 1 with the chamber 42 as the upper chamber and 41 as the lower chamber and they have not only been inverted but moved to the other side of the axis. They are, however, in such relation to a vertical plane that the material passing from the upper chamber 42 to the lower chamber will 30 result in the gradual movement of the center of gravity of the timer to the left in Figure 1 or away from the rotary axis, thus increasing the leverage by which the weight of the material tends to turn the timer further in the direction in which it was turned in opening the valve.
- 35 As will be seen by reference to Figure 4 when the valve has been moved to full open position and the operating arm 23 is in the position shown in full lines, a lateral projecting roller 62 on the end of a short arm 63 secured to shaft 36 of the timer is in contact with the end of a flat spring member 64 which spring is pivoted at 65 to the bar 37 and is supported by its lower shorter end portion 66 resting on the end of the screw 67 passing through an ear 68 carried by the bar 37. The strength of the spring 64 is 40 sufficient to prevent rotation of the timer to the left in Figure 1 due to gravity when first turned to position and the material is in the upper chamber of the timer but when the material passes down to the lower chamber 41 increasing the leverage tending
- 45 to turn the timer, its strength is not sufficient to resist the turning and is such that the timer will be released by it and turned downward in Figure 1 when the timing action is completed and the material has passed into the lower chamber. The screw 67 provides means for properly regulating the tension of the spring and its resistance to turning. A thin plate 69 is secured to the bar 37 above spring 64 in such position that it will 50 limit the upward turning movement of that spring and hold it in position to be engaged by the roller 62. In order to prevent an overthrow of the timer segment 35 by its momentum when the handle arm 23 is turned to open the valve a rod 70 is mounted in the projecting portion 22 of the valve and turns with it to the position shown in full lines in Figure 4 and is then in the path of and practically in contact with a laterally projecting lug 71 secured to the segmental gear 56 on the timer shaft and thus operates as a positive stop to limit any further turning of the timer due to momentum. However, when the operator releases the arm 23 the valve makes a slight reverse movement until the stop 28 strikes the end of catch 31 as heretofore described and this movement is sufficient to carry the rod 70 out of the path of the lug 71 whereby 55 the timer is no longer prevented from turning by it. The pin and slot connection 60 and 61 between the gear segment 57 and the valve permits this reverse movement of the valve without a reverse movement of the segments or the timer. When the timing action is completed and the material has all passed from the upper to the lower chamber of the timer it will, as above stated, be released by the spring 64 rotating 60 to the left under the influence of gravity and during that movement the laterally projecting roller 62 will strike the lower end portion 72 of the catch 31 thereby tripping it and moving it out of the path of the stop 28 on the valve permitting the valve to automatically and quickly close under the influence of the spring 25. There is a laterally extending projection 73 on the side of the segment 35 having an elongated surface in a radial plane and when the closing of the valve rotates the segment 35 back to the position shown in Figure 1 the face of this projection is immediately above the upper edge of the gear segment 57 and it serves 65 with that segment as a stop limiting further movement in preventing overthrow. It will be noted that the mechanism constituting the present invention occupies little space and may easily be enclosed in a suitable housing of simple form, as indicated in outline by dotted line 74 in Figure 1 although the casing forms no part of the present invention and is not shown.
- 70 As heretofore stated, Figs. 1 and 3 show

the mechanism in the position occupied when the valve is closed and at this time the hour-glass timer is in the position shown in Fig. 7 with the lower chamber 42 practically full of sand and the upper chamber 41 empty, and the coiled spring 25 surrounding the projecting end of the valve secured at one end to the valve casing and at the other end to the operating arm 23 is under tension tending to turn the valve and arm anti-clockwise, but this movement is prevented by the contact of the stop 28 rigidly secured to the end of the valve with the pin 27 rigidly secured to the valve casing. To open the valve, the arm 23 is manually turned to the right until the stop 28 on the valve strikes the end of stop 30 secured to the end of the valve housing. During this movement the gear segment 57 mounted on the outer end of the valve turns the same number of degrees as arm 23 and the gear segment 26, having a shorter radius but longer arc secured to the end of the shaft 36 rotatively supporting the hour-glass timer, turns simultaneously but at greater speed and through an arc of about 150°, causing the chamber 42 containing the sand, to move to a position at a higher level than the empty chamber 41. The stop 28, furthermore, during this movement, strikes the inclined lower surface of pivotal catch 31 between its pivot and contact end 33, turning that end out of its path against the tension of spring 34 which spring causes the catch to again move into the path of stop 28 when that stop passes beyond it and during this movement the rod 70, secured at one end to the valve, moves from the substantially vertical position shown in Figs. 1 and 3, to the left and to the nearly horizontal position shown in Fig. 4, with its end in the path of the lug 71 rigidly secured to the gear segment 56 on the timer shaft 36, thus serving as an automatic stop preventing overthrow of the timer when the operating arm suddenly stops. A small roller 62 rotatively mounted on a stub shaft secured to gear segment 56 on the timer shaft, moves during the said operation from the position at the right of the axis, as shown in Fig. 3, to the position at the left of the axis, shown in Fig. 4, resting on the upper convexly curved end portion of the leaf spring 64.

When the operator releases arm 23 at the end of its spring movement (see full lines Fig. 4) above described it will automatically, because of the tension of spring 26, move a short distance in the reverse direction (see dotted lines Fig. 4) until stop 28, secured to the valve, comes in contact with the end 33 of catch 31, and it should be noted that the gear segment 57 on the outer end of the valve does not make this short reverse movement with the valve and arm, but the headed pin 61, mounted on the end of the valve

and extending through the concentric arc-shaped slot 60 in the gear segment, moves from the lower end of the slot upwardly along it for a short distance and that the rod 70 moves from the full line position in the path of lug 71 to the dotted line position out of said path. 70

At this period of the operation the roller 62 rests on the end of leaf spring 64, which resists and temporarily prevents anti-clockwise movement of the timer and its gear segment 56, and the chamber 42 containing the sand is now the upper chamber, and as above stated the valve is positively held in open position against the tension of coiled spring 25 by the end 33 of catch 31 in contact with stop 28 on the valve. The valve remains fully open and the parts of the device immovable for a predetermined period of time during which the sand in the upper chamber of the hour-glass timer passes to the lower chamber at such angle to vertical and to the vertical plane of the timer axis of rotation, that the center of gravity will gradually move to the left of said vertical plane until the excess weight and leverage on that side of said plane are sufficient to overcome the resistance of leaf spring 64 and cause the roller 62 to bind the end of spring 64 out of its path and the timer and its gear segment 56 to rotate a short distance anti-clockwise. During this rotation the gear segment 57 on the end of the valve rotates a shorter distance in clockwise direction and there is a correspondingly short relative movement of the pin 61 in slot 60 in the same direction as in opening the valve. The roller 62 on the timer gear segment 56, after passing the end of spring 64 in its downward movement strikes the lower end portion 72 of the elongated pivotal catch 31 and causes it to turn on its pivot 32 sufficiently to raise its contact end 33 out of the path of stop 28 on the valve, thus allowing the tension of spring 25 to have full play in rotating the valve to closed position. The turning power of the spring is much greater than that of the gravity overbalance of the timer and the rotary movement of the timer and the gear segments 56 and 57 caused by said overbalance is at once interrupted and reversed and those parts, by reason of the gear connection, rotate with the valve back to the position normally occupied when the valve is closed, as shown in Fig. 1 and 3. 100

The contact of stop 28 on the valve with pin 27 on the valve casing limits this reverse movement of the valve and the contact of the elongated projection 73 on the side of the timer segment 35 with the upper edge of gear segment 57 serves as a stop for the timer and prevents overthrow (see Figs. 2 and 3). The relative position of the chambers of the timer being thus reversed, the 125

sand will automatically pass from the upper chamber 41 to the lower chamber 42 preparatory to the next operation.

Although one specific embodiment of the invention is shown for purposes of illustration, it will be understood that it is not limited to those details of construction beyond what is indicated in the following claims.

Having thus described the invention what is claimed as new and desired to be secured by Letters Patent is:

1. In a device of the class described the combination with a valve, of manually operable means for opening it, means or closing it, and means for causing said closing means to operate at the expiration of a predetermined time after opening including a timer of hour-glass form and means actuated by the opening means for moving said hour-glass timer to operative position.

2. The combination with a valve, of yielding means tending to move it to closed position, means for moving it to open position, automatic means for holding it in open position and automatic means for disabling said holding means at the expiration of a fixed time after opening including as the timing device a pivotally mounted hour-glass member which is moved to position for operation by the movement of the means for opening the valve and which at the expiration of its timing operation will move to effect the disabling.

3. The combination with a valve, of yielding means tending to move it to closed position, means for moving it to open position, automatic means for holding it in open position and automatic means for disabling said holding means at the expiration of a fixed time after opening including as the timing device a pivotally mounted hour-glass member which is moved to position for operation by the movement of the means for opening the valve which at the expiration of its timing operation will move to effect the disabling, means for regulating the size of the passageway connecting the chambers of the hour glass timing member whereby the elapsed time between opening and closing may be varied as desired.

4. The combination with a valve, of yielding means tending to move it to closed position, means for moving it to open position, automatic means for holding it in open position, a timer consisting of an hour glass member having a horizontal rotary support midway between its ends on one side whereby it will tend to turn by gravity when in operating position, means operated by the valve in opening for moving it to operative position but at a slight incline to the vertical whereby the vertical line through its center of gravity will change during operation, the means for turning it being so connected as to permit further limited movement beyond

that imparted by the opening means, yielding means so constructed as to temporarily prevent said further movement adapted to permit such movement by the action of gravity when the timing action is completed and the material has passed into the lower chamber of the timer, and means actuated by the timer during said further movement for disabling said means for holding the valve open thus permitting it to close.

5. The combination with a valve, of yielding means tending to move it to closed position, means for moving it to open position, automatic means for holding it in open position, a timer consisting of an hour glass member having a horizontal rotary support midway between its ends on one side whereby it will tend to turn by gravity when in operative position, means operated by the valve in opening for moving it to operative position but at a slight incline to the vertical whereby the vertical line through its center of gravity will change during operation, the means for turning it being so connected as to permit further limited movement beyond that imparted by the opening means, yielding means so constructed as to temporarily prevent said further movement adapted to permit such movement by the action of gravity when the timing action is completed and the material has passed into the lower chamber of the timer, and means actuated by the timer during said further movement for disabling said means for holding the valve open thus permitting it to close, and automatic means for temporarily interposing a positive stop to further movement of the timer at the end of the movement imparted by the opening means thus preventing overthrow.

6. In a device of the class described the combination with a valve casing of a rotary valve therein having limited rotary movement to open and closed position and yielding means tending to move it to closed position, means for manually rotating it to open position, an automatic catch for engaging and holding it in open position, a timer in the form of an hour glass at a slight angle to vertical pivotally mounted at one lateral side of its central portion by means of a shaft parallel to the axis of the valve, means operated by said opening means for turning said timer on its pivot approximately 150°, yielding means preventing further turning of the timer until its timing action is completed and the center of gravity is changed sufficiently to release it thus permitting further turning and means carried by said timer for tripping said automatic catch during such further turning movement thereby permitting the valve to close.

7. In a device of the class described the combination with a valve casing of a rotary valve therein having limited rotary movement to open and closed position and yield-

- ing means tending to move it to closed position, means for manually rotating it to open position, an automatic catch for engaging and holding it in open position, a timer semi-
5 cylindrical in outline mounted in a concentric rotary shaft parallel to the axis of the valve and having the characteristics of an hour glass, but set at a slight angle to vertical, a gear segment connected to the timer shaft
10 with its teeth in mesh with a gear segment carried by the valve and so related thereto that the opening of the valve will turn the timer approximately 150° , a stationary yielding spring catch adapted to be engaged by a
15 member connected to and movable with the timer when the valve reaches fully open position having just such strength as to prevent further movement of the timer until its contents have passed from one chamber to
20 the other and to then release it permitting further movement, and means whereby said member will in the further movement trip said automatic catch and allow the valve to close.
25 8. In a device of the class described the combination with a valve casing of a rotary valve therein having limited rotary movement to open and closed position and yielding means tending to move it
30 to closed position, means for manually rotating to open position, an automatic catch for engaging and holding it in open position, the engaging surfaces being so related that there will be a slight reverse
35 movement of the valve after it is moved to the limit of its opening movement before they will make contact, a timer semi cylindrical in outline mounted on a concentric shaft parallel to the axis of the valve and
40 having the characteristics of an hour glass, but set at a slight angle to vertical, a gear segment on the timer shaft, a gear segment carried by the valve, having limited relative rotary movement therewith with its teeth in
45 mesh with those of the timer segment and so related thereto that the opening of the valve will turn the timer approximately 150° , a stationary yielding spring catch adapted to be engaged by a member connect-
50 ed to and movable with the timer when the valve reaches fully open position having just such strength as to prevent further movement of the timer until its contents have
55 passed from one chamber to the other and to then release it permitting further movement, and means whereby said member will in the further movement trip said automatic catch and allow the valve to close, a member secured on the projecting portion of the
60 shaft in such position that it will be inter-
65 posed in the path of a fixed member carried by the timer and act as a positive stop for the timer preventing overthrow when the valve reaches the limit of its opening movement but which will be moved to inoper-

ative position by the reverse movement of the valve.

9. In a device of the class described the combination with a valve of means for moving it to open position, yielding means tending to close it, automatically operating but releasable means for holding it open, an hour-glass-like timer for disabling said holding means in the form of a segment of a cylinder mounted on a rotary axis concentric with its outer surface the connecting passageway between the chambers of the timer being in the form of a narrow opening extending radially midway between the ends of the segment, means connected to said valve for holding said timer on one side of its axis in one of its timing positions and for turning it to such inverted position on the other side of its axis when the valve is opened that the tendency to turn on the axis due to gravity will be increased by the passage of material from the upper to the lower chamber, a yielding stop preventing rotation but automatically releasing the timer at the end of its timing action and means operated by said timer for disabling the valve holding means when released.

10. In a device of the class described a timer having the main features and characteristics of an hour-glass and the outer form of a segment of a cylinder formed of thin material mounted on a rotary axis concentric with said cylinder, the inner surfaces of said segment near and on both sides of its central radial plane being inclined inwardly from the ends of said segment at a sharp angle longitudinally to said plane forming a narrow radial opening at that plane thereby forming two chambers in said segment with a small connecting passageway, a predetermined volume of sand-like material in the container formed by said chambers adapted to pass through said opening from one chamber to the other in a predetermined period of time, and automatic means for temporarily preventing further rotary movement when the timer is turned to a predetermined operative position in which the passage of material from one chamber to the other will move the center of gravity outward and for releasing it and permitting turning when the timing action is completed.

11. In a device of the class described a timer having the main features and characteristics of an hour-glass and the outer form of a segment of a cylinder formed of thin material mounted on a rotary axis concentric with said cylinder, the inner surfaces of said segment near and on both sides of its central radial plane being inclined inwardly from the ends of said segment at a sharp angle longitudinally to said plane forming a narrow radial opening at that plane thereby forming two chambers in said segment

with a small connecting passageway, a pre-determined volume of sand-like material in the container formed by said chamber adapted to pass through said opening from one chamber to the other in a predetermined period of time, and automatic means for temporarily preventing further rotary movement when the timer is turned to a predetermined operative position in which the passage of material from one chamber to the other will move the center of gravity outward and for releasing it and permitting

turning when the timing action is completed, a valve for said narrow opening in the form of an elongated thin plate with a straight edge slidably movable across said opening and means operable from the outer side of said segment for moving said valve to regulate the timing with the same amount of material. 15

In testimony whereof I hereunto affix my signature. 20

JOSEPH P. MEYER.
